HANDRAIL FOR BATHTUBS

Thomas D. Wallace, Winnebago, Minn.

Application June 16, 1948, Serial No. 33,395

8 Claims. (Cl. 4—185)

1

This invention relates to new and useful improvements in safety hand rails for bath tubs.

It is well known that many individuals have been seriously injured as a result of slipping and falling when attempting to get out of a bath tub, because of striking their heads or portions of their bodies against the bath tub, or some other fixed object, when they fall. This is readily understood because when a bath tub is wet and particularly when soapy, the surface thereof provides very little grip for an individual's foot, and because of the slippery condition of the bath tub, one may run the risk of falling each time he attempts to move about in the bath tub or tries to step out of it.

Numerous devices have heretofore been developed for use in conjunction with a bath tub whereby a person taking a bath may grasp a suitable handle or support conveniently located adjacent to the bath tub to thereby assist him in getting out of the tub. To the best of my knowledge, none of these devices have proven entirely satisfactory, and it is, therefore, an object of the present invention to provide a device of this type which may readily be applied to a conventional bath tub and which, when in operative position, may be conveniently grasped by a person to assist him in rising to a standing position within the tub and whereby he is not likely to slip and fall when moving about in the tub.

A further object is to provide a safety hand rail which is so constructed that it may be positioned transversely of the tub to thereby provide a rail which may be conveniently grasped by a bather sitting in the tub, when not in use, may be swung to an inoperative position parallel to a side wall of the tub.

A further object is to provide a hand rail for a bath tub having means for detachably securing it thereto, whereby said handrail may readily be detached from the bath tub, when not in use, if so desired, and which, when in operative position thereon, provides a substantial support which may be conveniently grasped by a bather when he proceeds to step out of the bath tub.

Other objects of the invention reside in the simple and inexpensive construction of the apparatus whereby it may be manufactured in quantity production at low cost; in the means provided whereby the hand rail may readily be applied to conventional bath tubs now in use without disturbing the mountings of such tubs; and in the means provided for locking the handle in operative position over the tub and also whereby it may readily and conveniently be released and swung to one side of the tub when not in use.

These and other objects of the invention and the means for their attainment will be more apparent from the following description taken in connection with the accompanying drawings.

2

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a view showing in perspective, a conventional bath tub to which the invention has been applied;

Figure 2 is a large cross-sectional view of a bath tub, showing the safety hand rail in operative position upon a bath tub;

Figure 3 is an enlarged detail sectional view showing the means for securing the swinging end of the hand rail in operative position;

Figure 4 is a cross sectional view substantially on the line 4—4 of Figure 3; and

Figure 5 is a detail sectional view showing a device for closing the upper ends of the guides provided in the side walls of the bath tub when the hand rail is detached from the bath tub.

In the selected embodiment of the invention herein disclosed, there is illustrated in Figure 1, for purposes of disclosure, a conventional bath tub 2, shown having one side positioned against a wall 3 and its head end positioned against a wall 4.

The novel invention herein disclosed comprises a transversely disposed hand rail, generally designated by the numeral 5. The hand rail has a horizontal portion 6 and a vertically disposed leg 7 adapted to be received in a tubular guide 8 provided in the back wall 9 of the tub, as best illustrated in Figure 2. The leg 7 may extend to the bottom of the guide 8.

When the safety hand rail is to be applied to a conventional bath tub already installed in a home, an opening 12 is cut in the upper horizontal or rolled edge portion of the back wall 9 of the bath tub of sufficient size to receive the tubular guide 8. The lower end of the guide 8 is closed by a plug or end plate 11 received in the bottom end thereof and preferably suitably secured therein, as by welding. A hole 13 is provided in the plug 11 adapted to receive a screw 14 which may be screwed into the floor 15, as indicated in Figure 2, when the guide is inserted through the opening 12 at the top of the bath tub with its lower end engaging the floor 15.

The overall length of the guide 8 is such that its upper end may project slightly above the top edge of the back wall 9 of the bath tub, and a suitable finishing cap 16 is then fitted over the upper end of the guide 8 to secure it in position within the space 17 at the back of the bath tub. The screw 14 may readily be secured in the floor with a long handled screw driver inserted into the upper end of the guide 8 before the leg 7 of the

hand rail is inserted into the guide. The face plate 16 may be secured to the top of the bath tub by suitable pins or screws 18, best shown in Figure 5.

A similar tubular guide 19 is provided in the front wall 20 of the bath tub within the space 21 provided within the inner and outer wall members 22 and 23, respectively, of the tub, as clearly illustrated in Figure 2. The tubular guide 19 differs slightly from rear tubular guide 8 in that it is shown having an interior longitudinally extending groove 24 cut in the wall thereof which extends downwardly from the top of the guide to a point intermediately thereof.

A lateral groove 25 leads from the vertical groove 24 and has its opposite end portion 26 terminating at a point about ninety degrees from the vertical groove 24, as shown in Figure 4. A transverse pin 27 is secured in a relatively short leg portion 28 having a flange 29 at its upper end forming a part of a coupling, generally designated by the numeral 31. The coupling 31 serves to secure the leg portion 28 to the depending leg portion 32 of the hand rail 5 at the front side of the bath tub.

The end 33 of the pin 27 projects beyond the periphery of the leg portion 28 and is adapted to be received in the vertical groove 24, as shown in Figures 3 and 4, and also in the transverse groove 25 by relative rotation of the leg portion 28 with respect to the front guide 19. The bottom of the front guide 19 is shown secured to the floor in a manner similar to the rear guide 8, and the parts thereof are, therefore, identified by like numerals. The same applies to the supporting means provided at the top of the guide 19.

Suitable finishing and closure caps 34, each comprising a plurality of spring-actuated prongs 35, are adapted to be detachably secured to the finishing plates 16 to close the openings therein, when the hand rail 5 is completely detached from the bath tub.

When the hand rail is in use, it is preferably positioned as shown in full lines in Figures 1 and 2, cross-wise of the bath tub, whereby a bather sitting in the tub may readily grasp the horizontal handle portion 6 and pull himself up to a standing position, or to assist in changing his position in the bath tub.

If the hand rail is not required, the coupling member 31 may readily and conveniently be manipulated to uncouple the leg portion 28 from the depending portion 32 of the hand rail, thereby permitting the hand rail to be swung into engagement with the back wall 3, as shown in dotted lines in Figure 1, where it may be completely out of the way of the bather. The front leg portion 28 may then be withdrawn from the front guide 19 after which a closure cap 34 is fitted over the opening in the upper end of the guide 9 to thereby prevent water and other foreign matter from dropping into the guide.

When the safety hand rail is in operative position, as shown in Figures 1 and 2, the leg portion 28 at the front of the bath tub may be rotated to a position to cause the projecting end portion 33 of the pin 27 to enter the lateral groove 25 in the guide 19, whereby the leg portion 28 is positively locked against axial or relative up-and-down movement within the guide 19. It will thus be noted that the rail is amply supported at the back and front of the tub whereby it may sustain considerable weight, and all such weight will be directed to the rail and its supporting means and not to the walls of the tub.

While the hand rail herein disclosed is well adapted for use as an attachment for a conventional bath tub already installed in a home, it is to be understood that it may readily be embodied in the construction of new tubs in which case the tubular guides 8 and 19 might be embodied directly in the tub structure to thereby become integral parts thereof.

The device may be finished in any color, but 10 is preferably chromium plated to match the fixtures of the tub, and when it is in operative position, as shown in Figures 1 and 2, it presents a very neat and attractive appearance.

It will be apparent to those skilled in the art 15 that I have accomplished at least the principal objects of my invention, and it will also be apparent to those skilled in the art that the embodiments herein described may be variously changed and modified without departing from the spirit 20 of the invention, and that the invention is capable of uses and has advantages not herein specifically described; hence it will be appreciated that the herein disclosed embodiments are 25 illustrative only, and that my invention is not limited thereto.

I claim as my invention:

1. A hand rail for bath tubs comprising a pair of guides having means for securing them laterally along the side walls of a conventional bath 30 tub, a hand rail of substantially U-shape having spaced legs received in said guides, and means, including a locking member connected to one of said legs and adapted interlockingly to engage the wall of its guide for locking the hand rail against movement in said guides.

2. A hand rail for bath tubs comprising a pair of guides having means for securing them laterally in spaced relation to the side walls of a conventional bath tub, a hand rail of substantially 40 U-shape having spaced legs received in said guides, means on one of said legs adapted slidably and rotatably to be received in the wall of its guide whereby the hand rail may be vertically adjusted, and means for locking the hand rail in adjusted position.

3. A hand rail for bath tubs comprising a pair of tubular guides having means for securing them to the opposed side walls of a conventional bath tub, the upper open ends of said guides 50 being disposed in proximity to the upper edges of the walls of the bath tub, and a hand rail comprising an upper transverse portion and spaced depending legs adapted to be received in said guides, one of said legs being substantially shorter than the other leg, whereby said hand rail may be raised upwardly until said shorter leg is free of its guide so that the hand rail can be swung to an out-of-the-way position.

4. A hand rail for bath tubs comprising a pair 60 of tubular guides having means for securing them laterally along opposite sides of the opposed walls of a conventional bath tub, the upper ends of said guides projecting slightly above the upper edges of the walls of the bath tub, a hand rail comprising an upper transverse portion and spaced depending legs adapted to be removably received in said guides, and means for securing the hand rail legs in said guides.

5. A hand rail for bath tubs comprising a pair 70 of vertically disposed tubular guides having means for securing them adjacent the side walls of a conventional bath tub and in spaced relation thereto, a hand rail having an upper horizontal portion and a depending leg adapted to be received in one of said tubular guides, a leg por-

tion detachably secured to the opposite end of the hand rail and adapted to be received in the other of said detachable guides, said leg portion having means adapted for interlocking engagement with its respective guides to lock the hand rail in position in said guides.

6. A hand rail for bath tubs comprising a pair of suitable vertically disposed guides secured in fixed positions in the usual side walls of a conventional bath tub, a hand rail having a main leg received in one of said guides, a relatively shorter leg received in the other of said guides and having means at its upper end for securing it to the opposite end of the hand rail and whereby the hand rail may be secured in fixed position with respect to the bath tub, detachment of said second leg portion from the hand rail permitting the hand rail to be swung to an out-of-the-way position adjacent to a wall against which the bath tub may be positioned.

7. A hand rail for bath tubs comprising a pair of suitable guides secured to the usual side walls of a conventional bath tub, a U-shaped hand rail having a horizontal portion adapted to be positioned over the bath tub and provided with spaced legs adapted to be received in said guides, and whereby the hand rail is conveniently located over the bath tub, one of said rails being detachable from one of said guides to permit the hand rail to be swung to an inoperative position over a side wall of the bath tub, means whereby the hand rail may be conveniently and com-

pletely detached from the guides and bath tub, when desired, and means for closing the upper open ends of the guides when the hand rail is detached from the bath tub.

8. A hand rail for bath tubs comprising a pair of suitable guides secured to the front and rear side walls of a conventional bath tub, a tubular hand rail comprising a horizontal portion adapted to be positioned over the bath tub and provided with a main depending leg adapted to be received in the guide at the rear of the bath tub, a relatively shorter independent leg portion removably received in the front guide and having means at its upper end for detachably securing it to the adjacent end of the hand rail whereby the hand rail may be locked against vertical and swinging movements in said guides, means whereby the hand rail may be conveniently and completely detached from the guides and bath tub, when desired, and spring-retained closure plates for closing the upper open ends of the guides when the hand rail is detached therefrom.
